UNITED STATES PATENT OFFICE

155,363

DESIGN FOR AN AIRPLANE

Calvin Thomas Ray, Baltimore County, and Carl Lawrence Brockman, Baltimore, Md., and Charles W. Butler, Leonia, N. J., assignors to The Glenn L. Martin Company, Baltimore, Md.

Application October 29, 1947, Serial No. 142,199

Term of patent 14 years

(Cl. D71—1)

To all whom it may concern:

Be it known that we, Calvin Thomas Ray, Carl Lawrence Brockman, and Charles W. Butler, citizens of the United States and residents, respectively, of county of Baltimore, State of Maryland; city of Baltimore, State of Maryland; and city of Leonia, county of Bergen, State of New Jersey, have invented a new, original, and ornamental Design for an Airplane, of which the following is a specification, reference being had to the accompanying drawings, forming a part thereof.

Figure 1 is a fragmentary perspective view of an airplane broken away to show the interior of the rear entrance compartment and passenger lounge.

Figure 2 is a fragmentary, sectional plan view of the corresponding portion thereof.

Figure 3 is a fragmentary, vertical sectional view of the corresponding portion thereof.

Figure 4 is a plan view of the complete airplane.

The characteristic features of our design reside in the portions shown by means of full lines in the drawing.

We claim:

The ornamental design for an airplane, substantially as shown and described.

CALVIN THOMAS RAY.

CARL LAWRENCE BROCKMAN.

CHARLES W. BUTLER.
